UNITED STATES PATENT OFFICE.

WILLIAM H. KUHNE, OF SAFETY HARBOR, FLORIDA.

WINDOW SCREEN.

Application filed May 8, 1924. Serial No. 711,848.

To all whom it may concern:

Be it known that I, WILLIAM H. KUHNE, a citizen of the United States, residing at Safety Harbor, in the county of Pinellas 5 and State of Florida, have invented certain new and useful Improvements in a Window Screen, of which the following is a specification.

This invention relates to window screens 10 and it consists in the novel features herein-after described and claimed.

An object of the invention is to provide a window screen structure including tracks adapted to be applied to the inner surfaces 15 of the upright sides of a window frame and frames mounted for movement along the tracks. The said frames are adapted to retain screens or glazed sashes and the tracks are composed of sections, some of which are fixed to the window frame and other of the 20 sections are pivotally mounted whereby they may be swung out of alignment with the fixed sections and the said frames may be readily removed from the tracks without 25 detaching the tracks from the window frame.

In the accompanying drawings:—

Figure 1 is a side elevation of a window 30 frame with the screen applied.

Figure 2 includes views of the sections of one of the guide tracks.

Figure 3 is a fragmentary side elevation 35 of the corner portion of one of the supplemental frames and guide track.

Figure 4 is a horizontal sectional view thereof cut on the line 4—4 of Figure 3.

Figure 5 is a transverse sectional view 40 thereof cut on the line 5—5 of Figure 3.

Figure 6 is an enlarged side elevation of 45 the lower corner of one of the supplemental frames.

Figure 7 is a transverse sectional view 50 thereof cut on the line 7—7 of Figure 6.

Figure 8 is a fragmentary view of the 55 corner portion of one of the screen frames.

Figure 9 is a transverse sectional view 60 of the screen frame, the section being taken approximately on the line 9—9 of Figure 8.

Figure 10 is an enlarged detailed side elevation 65 of one of the sections of the guide track.

Figure 11 is a side edge elevation of the 70 same.

Figure 12 is a transverse sectional view 75 of the track section cut on the line 12—12 of Figure 10.

The window screen structure includes two

guide tracks 1 which are mounted at the inner surfaces of the side uprights of the main window frame. Each guide track includes one intermediate section 3 which is pivoted at a point midway between its ends as indicated at 4 in Figure 2, to the side of the window frame 2. The section 3 is provided with spaced guide channels 5 disposed in spaced parallelism. The track also includes two terminal or end sections 6 which are fixed to the side of the frame 2 and which also include spaced guide channels aligned with the guides 5 of the intermediate track sections. The sections 3 and 6 are beveled at their adjacent ends so that the section 3 may swing upon its pivot 4 and with relation to the sections 6.

Supplemental frames 7 are arranged to slide between the guide tracks 1 which are mounted at the opposite sides of the window frame 2 and the frames 7 are composed of spaced side strips 8 which are connected with each other by means of rivets 9 passing through flanges 8^a and strips 10 are slidably mounted between the strips 8. The strips 10 are provided with transversely disposed slots 11 which receive rivets 12, the said rivets being secured to the flanges 8^a. The extended edge portions of the strips 10 are adapted to move along the guides 5 of the track sections. The space between the upper edges of the strips 8 of the upper frames 7 is closed by a cap strip 15 as best shown in Figure 5 of the drawing. A screen frame 13 may be inserted in each of the frames 7 or should it be desired sash frames and a glass panel may be inserted in the frames 7 in lieu of the screen frames 13. The lower frame 7 is provided at its upper portion with a catch member 14 adapted to engage the lower rail of the upper frame 7 when the said frames are extended within the window frame 2 as shown in Figure 1 of the drawing and whereby the upper frame 7 is held at an elevated position between the guide tracks 1. When it is desired to remove the frames 7 from the tracks 1 and the window frame 2, said frames 7 are moved into the guides 5 of the intermediate track sections 3 and then the said sections are swung, substantially to the position as shown in Figure 2 of the drawings when the frames 7 may be slipped out of the lower ends of the guides 5. By reversing the operation just described the frames 7 may be reinserted between the tracks and within

the window frame 2. When the sections 3 are in alignment with the terminal sections 6 the frames 7 may move the full length of the tracks 1 and when the strips 10 of the frames 7 bridge the joints between the intermediate sections 3 and the terminal sections 6 of the tracks 1, the said sections are held in vertical alignment with each other.

From the foregoing description taken in conjunction with the accompanying drawings it will be seen that a window screen structure is provided and in which the screen frames or the sash frames may be readily and easily detached from the window frame for the purpose of cleaning, storage or the like. Also the strips of the slideable frame effectually close the window opening and prevent the passage of flies or mosquitoes through the window openings.

Having thus described the invention, what I claim is:

1. A window screen structure comprising

tracks applied to the sides of the window frame, each track including an intermediate pivoted section and terminal fixed sections, said sections having beveled adjacent ends, frames located between the tracks, the pivoted track sections being longer vertically than the frames and the frames being longer vertically than the fixed track sections.

2. A window screen structure comprising tracks applied to the sides of the window frame, each track including an intermediate pivoted section and terminal fixed sections, said sections having beveled adjacent ends, all of the sections being provided with spaced guide ways, frames located between the tracks, said frames being provided at their sides with strips, said strips having transversely disposed slots and rivets carried by the frames and passing through said slots.

In testimony whereof I affix my signature.

WM. H. KUHNE.
